United States Patent Office.

EDWIN A. WOOD, OF UTICA NEW YORK.

Letters Patent No. 76,965, dated April 21, 1868.

IMPROVEMENT IN ELECTRO-MAGNETIC VALVE-GEAR.

The Schedule referred to in these Letters Patent and, making part of the same.

TO ALL WHOM IT MAY CONCERN:

Be it known that I, EDWIN A. WOOD, of Utica, New York, have invented a new and useful Improvement in Cut-Off Valve-Gear.

The nature of my invention consists in the use of electro-magnets, one or more, for connecting and detaching the valve or valve-stem with and from the eccentric-rod or other part of the engine which operates the valve, whether the same be inlet-valves, independent cut-offs, or governor-valves; and I do hereby declare that the following is a full, clear, and exact description of my said invention, and of the mode of operation of the same, reference being had to the annexed drawings, making a part of this specification, in which—

Figure 1 represents a side view thereof, and

Figure 2 an end view thereof.

A is the steam-cylinder; B B' are the valve-casings; C C', valve-stems; C' C', arms attached thereto; D D', armatures connected with said arms; E, sliding frame; E' E', cross-bars thereof; F F', electro-magnets; F², connecting-bar between; G, galvanic battery; H, a support for H¹ H², metallic plates; H³, connection between H¹ and H²; I, governor; I', knob on end of fine rod or wire I², on end of governor-spindle; K, eccentric-rod.

The valves may be of any form which will permit the steam to be cut off at any part of the stroke of the piston. The drawings represent oscillating-valves.

The valve-stems C have each an arm, C', to the lower end of which is attached a block of iron, D D', which form armatures for the electro-magnets. D and D' are attached to their respective arms, C' C', by a pin running through the centre. This allows the armature to remain horizontal while the arm oscillates in moving the valve.

A sliding frame, E, connects the two armatures D and D'. This frame is composed of two metallic bars, one above and the other below D and D', and are connected together near the centre by two cross-bars, E' E'. The electro-magnets F and F' are placed in this frame, each facing their respective armatures, D and D', while the opposite ends are united by the bar F² running through the cross-bars E' E'. The inner ends of the wires of the two magnets are united as seen in the drawing. On the inner side of the slide E, and extending from cross-bar to cross-bar E' E', is a vertical support of non-conducting material, H. On the face of H are two metallic plates, H¹ and H², of the same nearly-triangular form, with the narrowest ends downwards, and with a connection near the top, H³. Over the sliding frame E, and at the centre of the cylinder, is the governor I, which may be driven in any of the well-known ways. The lower end of the spindle extends into a fine rod or wire, I², having a knob, I', on its lower end. The outer end of the insulated wire of F' is connected with the plate H², and the outer end of the wire on F is connected with one pole of the battery G. The other pole of the battery is connected with the governor, as seen in the drawing. To the under side of the slide E is attached the eccentric-rod K. The slide E, with the magnets F and F', therefore, have the motion of the eccentric-rod. As the slide moves back and forward, the knob I' touches the plates H¹ and H², and while it so touches either, the galvanic circuit is complete, and is broken when the knob I' is in the space H, between the plates.

The operation is as follows: Steam may be let on in the usual way, when the eccentric will carry the magnets F and F', alternately, towards and from each armature D and D', when each magnet in turn will attach itself to its armature, by means of which the valve with which it is connected will be opened and remain so until the knob I' has passed over H¹ or H², when the galvanic circuit will be broken, which will free the armature from the magnet, and the valve will close by the weight, spring, pressure of the steam, or whatever means may be used for that purpose. Thus if the valve B' is first opened, the eccentric will draw the magnet F against D, which will bring the plate H² against the knob I', and thus make the circuit complete, and the magnet will hold on to the armature D. On reversing the eccentric, the valve B will be drawn open, and remain open while I' passes over H², when the circuit is broken and the valve released, which will instantly close, and the eccentric continuing on, will next press the magnet F' against D', when the plate H¹ will touch I', and again

make the circuit complete, and on reversing the eccentric, the valve B' will be drawn open, and remain open until I' has passed H¹, when the circuit will be broken, and the armature will be detached, and the valve B' will close, and so on.

As the speed of the engine increases, the governor causes the knob I' to descend, and to rise as the motion becomes slower, and as the width of the plates H¹ and H² diminish downwards, the higher the knob I' is at any time in passing either plate H¹ or H², the longer the valve will be kept open and allow of a larger amount of steam to follow the piston, and, on the contrary, the lower the knob is, the shorter time the valve will be kept open, and the quicker the steam will be cut off. As the governor has no labor to perform in opening valves, and no friction to overcome but that arising from its supports and the closing of the galvanic circuit, it may be of the simplest form, and will of course be quite sensitive. Should the belt fly off from the governor, the knob I' will be drawn above the plates H¹ and H², and consequently there can be no galvanic circuit, and the engine must stop.

The advantages of this invention are: It reduces cut-off-valve gear to the greatest simplicity; it allows the governor to be of the most sensitive character, and makes the cut-off obey its slightest movements; it thus reduces the cost of the engine, as well as of running it, for there can be no waste of steam, and the governor also becomes a perfect safety-governor, for if its belt flies off, the engine must stop.

Instead of two valves, as described, only one may be used, and instead of using the electro-magnet on the inlet-valve or valves, as described, it may be used on an independent cut-off or governor-valve. When other forms of valves than those described in the drawing are used, the changes necessary to adapt the magnet and armature to such change will readily occur to every competent mechanic. The magnets F and F' are, in effect, a single one, and may be so made.

It is apparent that the electro-magnet may be applied in a great variety of ways to effect this purpose. That described is simple, but other forms may be used without affecting the principle.

I do not, therefore, wish to confine myself to the mode of construction or parts herein described; but

I claim as my invention, and desire to secure by Letters Patent—

1. The use of the electro-magnet, one or more, for connecting and detaching the cut-off or governor-valve or valves of a steam-engine, with and from the power which operates such valve or valves, as described.

2. The use of the governor and electro-magnet, one or more, in combination with the inlet cut-off or governor-valve or valves of an engine, for the uses and purposes mentioned.

EDWIN A. WOOD.
